UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,292,165.

Specification of Letters Patent. Patented Jan. 21, 1919.

Application filed October 7, 1915. Serial No. 54,522.

To all whom it may concern:

Be it known that I, JESSE G. VINCENT, a citizen of the United States, and resident of Detroit, Wayne county, State of Michigan, have invented certain new and useful Improvements in Hydrocarbon-Motors, of which the following is a specification.

This invention relates to hydrocarbon motors, and particularly motors having cylinder blocks arranged side by side. In the 10 form of the invention chosen for illustrative purposes a V type motor is shown.

One of the objects of the invention is to provide a novel and convenient arrangement 15 of the carbureter and intake piping of a V or similar type motor.

The above and other objects of the invention will appear from the following description taken in connection with the 20 drawing which forms a part of this specification, and in which the figure represents a vertical transverse section through a motor embodying the invention.

Referring to the drawing, 10 represents 25 the motor base or crank case having suitable supporting arms 11. A crank shaft 12 is mounted in bearings 13 in the crank case, and is arranged to drive (through gearing not shown) a cam shaft 14 which is shown 30 as arranged vertically above the crank shaft.

Formed with or mounted side by side upon the crank case 10 are two blocks of cylinders 15, shown as suitably water-jacketed as at 16, and provided with valves 35 17, valve springs 18, and push rods 19, the latter of which coöperate with the cam shaft 14 in the usual way. Other appurtenances of the motor are the spark plugs 16' and exhaust manifolds 16''.

40 It will be understood that each of the cylinder blocks comprises several cylinders, preferably six, and formed integral therewith or properly secured thereto longitudinally along its inner side is an intake manifold 20. These manifolds 20 connect with the intake passages to the combustion chamber in the usual way. For manufacturing advantages, both cylinder blocks are cast exactly alike, and as shown, each of them is formed with a cross channel or passage 21, approximately in the middle of the block and extending from one side to the other and communicating with the manifold 20. On one side of the motor, that is, in one of 45 the blocks, the passage 21 is closed as by a

plug 22 arranged adjacent its inner end, and the outer end of the passage may be closed by a plate 23. The cross passage 21 on the other side of the motor, the right side in the figure, communicates with the carbureter 24 60 by a pipe 25. Thus the combustible mixture from the carbureter is led into the cross channel 21 and into the manifold 20 of the right cylinder block, and said manifold supplies all of the cylinders of that block. 65

A connecting pipe 26 is arranged between the two manifolds 20 and thus conveys some of the combustible mixture from the manifold of the right hand cylinder block to the manifold 20 of the left hand cylinder block. 70 The latter manifold supplies the mixture to all of the cylinders of that block.

This connecting pipe 26 is shown as fitting nicely between pipe extensions 27 on each of the manifolds 20, the adjacent edges 75 of the pipe and pipe extensions being grooved to form seats for rings 28 which are preferably formed of rubber or similar material. These rings 28 not only hold the connecting pipe 26 in position, but also close the 80 joint between said pipe and the pipe extension 27, and permit of ready removal of said pipe.

It will be understood that while but one 85 form of the invention is illustrated and described herein, other forms may be used and changes may be made without departing from the spirit or scope of the invention.

Having thus described my invention, what I claim and desire to secure by Letters Patent is:—

1. The combination with a V-type hydrocarbon motor having two blocks of cylinders with intake manifolds arranged along the inner sides of the cylinders, of a carbureter 95 arranged at the outer side of one of the cylinder blocks, and means passing through one of said cylinder blocks for connecting said carbureter with both of said intake manifolds.

2. The combination with a V type hydrocarbon motor having longitudinal intake manifolds, of a tube connecting said manifolds and a carbureter arranged at the outer side of the cylinders and connected to one 105 of said manifolds and supplying the other manifold through said tube.

3. The combination with a hydrocarbon motor, having cylinder blocks arranged in parallel, each of said blocks having a longi- 110

- tudinal intake manifold and one of said blocks having a cross passage communicating with an intake manifold, and a pipe connecting said manifolds, of a carbureter communicating with said cross passage.
4. The combination with a hydrocarbon motor having cylinder blocks arranged in parallel, each of said blocks having a longitudinal intake manifold along its inner side and one of said blocks having a cross passage communicating with an intake manifold, and a pipe connecting said manifolds, of a carbureter communicating with said cross passage.
- 10 5. The combination with a hydrocarbon motor having cylinder blocks arranged in parallel, each of said blocks having a longitudinal intake manifold and one of said blocks having a cross passage communicating with an intake manifold, and a pipe connecting said manifolds, of a carbureter arranged at the outer side of the cylinder block having the cross passage and communicating with said passage.
- 20 6. The combination with a hydrocarbon motor having cylinder blocks arranged in parallel, each of said blocks having a longitudinal intake manifold and a cross passage communicating therewith, and a pipe

connecting said manifolds, of a carbureter 30 arranged at the outer side of one of said blocks and communicating with one of said cross passages, and a plug for the other said cross passage.

7. The combination with a hydrocarbon 35 motor having cylinder blocks arranged in parallel, each of said blocks having a longitudinal intake manifold along its inner side and a cross passage communicating therewith, and a pipe connecting said manifolds, 40 of a carbureter arranged at the outer side of one of said blocks and communicating with one of said cross passages, and a plug for the other said cross passage.

8. The combination with a hydrocarbon 45 motor having cylinder blocks arranged in parallel, each of said blocks having a longitudinal intake manifold along its inner side and a centrally arranged cross passage 50 communicating therewith, and a pipe connecting said manifolds, of a carbureter arranged at the outer side of one of said blocks and communicating with one of said cross passages, and a plug for the other said cross passage.

55 In testimony whereof I affix my signature.

JESSE G. VINCENT.
